REMOTE CONTROL APPARATUS FOR THE
SUCCESSIVE RELEASE OF BOMBS IN AIR-
CRAFTRaymond Defives, Brussels, Belgium, assignor to
Servo-Frein Dewandre Societe Anonyme, Liege,
BelgiumApplication April 1, 1937, Serial No. 134,419
In France April 8, 1936

4 Claims. (CL 89—1.5)

My invention relates to an apparatus for remotely controlling the release of bombs on board aircraft and relates particularly to a device for ensuring the successive fall of the bombs.

5 According to the invention the support of each bomb is provided with a release mechanism established in such a way that the operation of the release mechanism of a first bomb upon the actuation of the control member actuated by 10 the operator automatically puts the said control member in communication with the release mechanism of a second bomb, each mechanism being put into the operative position by means of a locking system actuated by the putting into position of each bomb.

An example of embodiment of the invention in its application to a pneumatic device will be hereinafter described with reference to the accompanying drawings in which:

20 Figure 1 shows a diagrammatic view of the apparatus assembly and of the bomb secured to the aeroplane;

Figure 2 is a view in longitudinal section of the control mechanism shown in its unlocking position;

25 Figure 3 is a front view of the mechanism shown in Figure 2;

Figure 4 is a view similar to Figure 2 showing the mechanism in its unlocking position;

30 Figure 5 is an end view of the bomb showing the means for securing it on its support;

Figure 6 is a diagrammatic view of the aeroplane showing the arrangement of the bombs and the release mechanisms with pneumatic fluid circuit;

35 Figure 7 shows a modification of the device for attaching the bomb to the aeroplane.

In these figures, a support 10 secured to the aeroplane is provided with a socket 11 or the like in which engages a lug 12 provided on the bomb 13 for its attachment by means of a pin or pull out piece 14 engaged in apertures provided in the socket and in the said lug.

40 V shaped abutment members 15 (Figures 1 and 5) secured to the support 10 are intended to hold the bomb 13 in a suitable position.

The pull out piece 14 is pivotally connected by a rod 16 to the end of an oscillating lever 17 pivoted at 18 and subjected to the action of a spring 19 secured to the support 10.

45 A rod 20 further connects the said lever 17 to the end of a lever 21 pivoted at 22 to an extension 23 provided on the body 24 of the actuating mechanism secured to the support 10.

50 The said mechanism comprises a cylinder 25

closed at 26 and in which slides a piston 27 the rod 28 of which presents a transverse recess 29. In the latter is engaged the lever 21 which is guided by a driving pivot 30 extending into a diametral boring of the said rod and into an eyelet provided on the said lever 21.

5 Parallel to the cylinder 25 and at the side of it, the body 24 is provided with a two valve distributor 31 and 32, said valves being connected together by a rod 33.

10 The first of these valves is intended to cut off communication between the cylinder 25 and the source of pneumatic fluid delivered by the conduit 34.

The valve 32 is provided for cutting off communication between the conduit 34 and the conduit 35.

15 The said valves are urged by springs 36 and 37 acting respectively behind the valve 31 and on a guide piston 38 integral with the control rod 39 of the said valves.

20 In a transverse guide 40 secured to the body 24 is guided a bolt 41 subjected to the action of a spring 42 and presenting a median constricted part in which an aperture 43 permits 25 the sliding of the rod 39.

25 The said bolt is intended to automatically engage a groove 44 notched in the said rod 39 when the latter is moved against the opposition of springs 37 and 36 and when the valve 32 is 30 brought into its closed position while the valve 31 is brought into its open position.

30 The displacement of the said rod 39 is effected under the action of a lever 45 pivoted at 46 to the casing of the mechanism and provided 35 with a stop 47 intended to act on the end 48 of the rod 39 when the said lever 45 is displaced angularly in a clockwise direction in order to permit the bomb 13 to be placed in position on the support 10.

35 A ball latch 49 is provided in order to operate 40 on the lever 45 and to hold it stationary in its extreme angular positions.

40 A tappet 50 pivoted at 51 on the rod 28 is intended to act on a boss 52 of the bolt 41 and 45 is normally held against a stop 53 of the said rod 28 by the action of a spring 54.

45 The different bomb supports provided with their release mechanisms are secured for example under the wings of the aeroplane as shown 50 in Figure 6.

55 This figure further shows a compressed air tank 55 connected by means of an expansion valve 56 to a selector valve 57 intended to put the ducts 58 and 58a in communication either 55

with the tank of fluid or with the atmosphere.

The duct 58 extends from the valve 57 to the conduit 34 of the release mechanism of a bomb A while the conduit 35 of this mechanism is connected by a tube 59 to the conduit 34 of the mechanism of a bomb B the conduit 35 of which is connected to the mechanism of a bomb C and so on for each following bomb. The arrangement shown for the series of bombs in the right wing of the aeroplane is identical with that of the series of bombs on the left wing.

In order to maintain the equilibrium of the aeroplane during the fall of the bombs, the fluid distribution is preferably established in such a way as to produce simultaneously the release of one bomb of the series on the right wing and one bomb of the series on the left wing, it being understood, nevertheless, that the selector valve 57 may be arranged so as to release only one bomb at a time.

The operation of the apparatus is as follows:

The lever 45 having been necessarily actuated in order to put the bombs in position on their support, the valves of the different bomb mechanisms become locked by the bolt 41 in the position shown in Figure 4. In this position of the valves the cylinder 25 of the first bomb is in communication with the tube 58 while the tube 59 connecting the mechanism of this first bomb to the next is isolated by the closure of the valve 32.

If it is desired to release a first bomb from each wing, the operator after having opened the selector valve 57 operates on the expansion valve 56 in order to send through the ducts 58 and 58a, the compressed air which passes through the conduit 34 of the bombs A of each wing and operates in the cylinder 25 in order to displace the piston 27 and the rod 28. The latter in its movement moves the lever 21 which in its turn actuates the rod 20, the lever 17 and the rod 16 which disengages the pull out piece 14 from the lug 12 of the bomb. During the movement of the rod 28 the tappet 50 rocks on the boss 52.

So long as the operator bears on the expansion valve 56 the piston 27 remains at the bottom of its stroke and a single bomb from each wing is released.

As soon as the operator ceases his action on the valve 56 putting the channels 58 and 58a and the cylinder 25 of the mechanisms of the bombs A of each wing in communication with the atmosphere, the piston 27 returns to its original position urged by the action of the spring 19 actuating the lever 17. The return movement of the piston 27 causes the tappet 50 to act on the boss 52 pushing back the bolt 41 against the action of the spring 42 while disengaging the said bolt from the groove 44. Under the action of the springs 37 and 36 the valves 32 and 31 take up their position shown in Figure 2. The valve 31 is then closed cutting off communication between the cylinder 25 and the conduit 34 whereas the valve 32 is opened establishing communication of the conduit 34 with the conduit 35. During its movement the rod 39 operates by its end 48 on the stop 47 of the lever 45 which falls and takes up the position shown in Figure 1 and is held in this new position by the action of the ball 49.

In this latter position of the valves of the mechanism of the bomb A of each wing the compressed fluid can now pass to the mechanism of the bomb B of each wing while passing through the channels 58 and 58a, conduits 34 and 35 and the tubes 59 and 59a. A fresh action of the operator on the expansion valve 56 in order to

establish communication of the tank 55 with the tubes 58 and 58a will have the effect of producing the release of the bomb B of each wing.

As will be seen the complete safety of distribution is ensured since it is necessary to cease the action of the expansion valve 56 in order to be able to release the next bomb. The release of the bombs C and D is effected as for the first two bombs but causing the fluid to pass through the different release devices of the bombs which have previously fallen and in each of which the valve 32 is open and the valve 31 is closed.

The selector valve 57 provided at a point of the cockpit within reach of the pilot further permits the control of the bomb release to be isolated when it is desired to pneumatically control other firearms such as machine guns, cannons, etc., fitted on board the aeroplane. The expansion valve in this case serves to actuate the various firearms.

The bombs may also be supported vertically according to the arrangement shown in Figure 7. In this arrangement the bomb attachment in which is engaged the pull out piece 14 is then provided at one end of the projectile.

What I claim is:

1. In a remote control device for actuating successively, on board an aeroplane, fluid motor operated bomb releasing mechanisms, a fluid motor for each of said mechanisms, a distributor for each of said motors, a source of fluid under pressure, a conduit for connecting the said source of fluid with the said distributor, a member for cutting off the pressure of fluid in the said conduit, a first valve in the said distributor, a spring for acting upon the said valve to normally close the communication between the said conduit and the said motor, a second valve in the said distributor, a second spring for acting upon the said second valve to normally open the latter and establish the communication between the said conduit and the driving means for the bomb release mechanism to be actuated next, a positive connection between the said first and second valve, means for automatically locking the said first and second valve after a movement of these valves against the opposing action of the said first and second spring, and means associated with the motor co-operating with the said distributor, for unlocking the said first and second valve when the pressure is cut off in the said conduit upon operation of the said motor.

2. In a fluid operated remote control device for successively actuating on board an aeroplane, a number of bomb release mechanisms by means of fluid motors, a fluid operated motor for each of the said mechanisms, a fluid distributor associated with each of the said motors, a source of fluid under pressure, a conduit for connecting the said source of fluid to the said distributor, a member for cutting off the pressure in the said conduit, valves in the said distributor for being simultaneously actuated against the opposing action of resilient means and for alternately opening the communication between the said conduit and the said motor, and with the controlling means of the bomb release mechanism to be actuated next, a rod for operating the said valves, an annular groove in said rod, a loaded bolt provided transversely of the said rod and subjected to the action of a spring to engage automatically the said groove when the said valves are driven and are establishing the communication between the said conduit and the said fluid motor, a cylinder for the

- 5 said fluid motor, a piston in this cylinder, means opposing the displacement of the said piston, a piston rod for the said piston, a loaded pawl pivoted to the said piston rod for acting upon the said bolt and for disengaging the latter when the pressure is cut off in the said conduit upon operation of the said fluid motor, and means moved by the action of fastening a bomb to the said mechanism, for operating the said valves.
- 10 3. In a fluid operated remote control device for actuating successively, on board an aeroplane a number of fluid motors driving each a bomb release mechanism, a base for the said mechanism, a recessed support secured to the said base for engagement by an eye associated with a bomb to be released, a transverse aperture in the said eye, a transverse aperture in the said recessed support, a pull pin engaging the aperture in the said recessed support and the aperture in the said eye, a 15 motor cylinder supported on the said base, a piston in said cylinder, resilient means opposing the movement of the said piston, a piston rod associated with the said piston, a linked connection for uniting the said piston rod to the said pull pin, a fluid distributor integral with the said cylinder, a source of fluid under pressure, a conduit for connecting the said source of fluid with the said distributor, a member associated with the said conduit for cutting off the pressure of fluid in the 20 latter, controlling members in said distributor,
- 25
- 30

means for actuating the said controlling members by the action of fastening a bomb to the said mechanism and for opening the communication between the said conduit and the said motor cylinder, and means subordinate to the pressure cut-off in the said conduit for closing the connection between the latter and the said cylinder and for opening the communication between the said conduit and the controlling means of the bomb release mechanism to be actuated next.

4. In a remote control apparatus for successively actuating bomb-release mechanisms of an air-craft controlled by fluid motors, a source of compressed fluid and a conduit for connecting the motors with said source, a member in the conduit 15 for cutting off the pressure of the fluid, a bomb support for each of the bomb-release mechanisms, a fluid cylinder for each mechanism, a movable member in said cylinder for actuating said mechanism when moved under the action of the fluid, 20 a spring acting on said movable member to return it to its normal position, a three-way distributor for providing communication of said motor with said conduit when arranging a bomb in position, means provided on said movable member to act 25 during the return stroke of the latter and cause said distributor to return into a position for establishing communication of the conduit with the motor of the following mechanism to be actuated.

RAYMOND DEFTVES. 30
